ATTORNEY

UNITED STATES PATENT OFFICE.

VESPER I. ARMSTRONG, OF CARTERVILLE, MISSOURI.

MUSIC-HOLDER.

1,270,767.

Specification of Letters Patent.

Patented July 2, 1918.

Application filed December 4, 1916. Serial No. 135,024.

To all whom it may concern:

Be it known that I, VESPER I. ARMSTRONG, a citizen of the United States, residing at Carterville, in the county of Jasper and State of Missouri, have invented certain new and useful Improvements in Music-Holders, of which the following is a specification.

This invention relates to a music holder and more particularly to the class of music 10 lyres for holding and supporting sheet music and band books on musical instruments whereby the music may be readily observed by the player of the instrument.

The primary object of the invention is to 15 provide a device of this character for securely holding the leaves of music in a vertical position regardless of the angle at which the musical instrument is held by the player.

20 A further object of the invention resides in the provision of a music holder of this character which includes a supporting plate against which the music leaves contact whereby their displacement from a gust of 25 wind will be prevented when the device is in use in connection with band instruments.

Another object of the invention resides in the provision of a supporting plate provided with fastening elements on each of its 30 flat surfaces whereby the leaves of music may be supported on either the front or rear surfaces of the supporting plate.

Another object is the provision of a pivot 35 supporting plate provided with means for angularly adjusting the plate so that the same may be held in vertical position when the supporting standard for the plate is disposed at an angle to the musical instrument to which it is secured.

40 The above and additional objects are accomplished by such means as are illustrated in the preferred embodiment and in the accompanying drawing, wherein like characters denote like or corresponding parts throughout the several views, in which:—

Figure 1 is a front elevation.

Fig. 2 is a rear elevation.

Fig. 3 is an edge elevation.

50 The supporting standard 1 shown in the drawings as partly broken away, is constructed to have its lower end connected to any design of musical instrument and its upper end is provided with an aperture for receiving a pivot pin 2 connected to the supporting plate 3 adjacent the center of the

plate so that the plate may be moved on the pivot to any desired angle. Many players of musical instruments, especially cornet players or other similar small instruments, find it desirable to hold the instrument at 60 an angle when in marching formation and, of course, unless provision is made for the music, the same will be held at an angle when the instrument is being played. The pivotal movement of the supporting plate 65 3, therefore, provide for the angular disposition of the instrument at the same time the music is retained in a perfectly vertical position where it may be conveniently read by the player. 70

For holding the supporting plate in the desired angular position, the lower edge of the plate carries an ear 4 to which is pivotally connected the adjusting arm 5 having its free end provided with a plurality of 75 longitudinally spaced apertures 6. The standard 1 carries a locking pin 7 adapted to extend through one of the apertures 6 and provided with a thumb nut 8. It will be readily apparent that when the arm 5 80 is removed from engagement with the locking pin 7 and one of the other apertures in the arm is engaged with the locking pin and secured by the thumb nut 8 the plate will be held at any pre-determined angle. 85

The front side 9 of the plate 3 carries, in close proximity to each corner of the plate, a clip 10 adapted to receive the corners of the leaves of music or the corners of the band book whereby the same may be 90 securely held in engagement with the front of the plate 3. The back surface 11 of the supporting plate 3 is also provided with a pair of clips 12 for suspending the leaves of music therefrom when it is desired and 95 also when a surplus number of sheets of music are to be primarily disposed of, when the music on the front surface of the plate is being executed.

From the foregoing it will be observed 100 that a very simple and durable music holder has been provided, the details of which embody the preferred form. I desire it to be understood however, that slight changes in the minor details of construction may be 105 made without departing from the spirit of the invention or the scope of the claims hereunto appended.

I claim:

1. A music holder comprising a plate, a 110

standard pivotally connected to the plate at a point near the center thereof, so as to permit the plate to swing in its own plane, the lower marginal edge of the said plate at 5 a point at one side of the center being provided with an ear, the said standard having a pin fastened thereto at a point considerably below the lower marginal edge of the said plate, and an arm pivotally connected 10 to the said ear and having a plurality of apertures removably engageable with the said pin.

2. A music holder comprising a rectangular plate, a standard pivotally connected 15 to the plate at a point near the center thereof, for permitting swinging movement of the said plate on the standard in its own plane, and an ear fastened to the lower mar-

ginal edge of the plate at a point near one end thereof, and an arm having one end pivotally connected to the ear and adapted to be normally obliquely disposed and having its opposite end projected across the said standard at an angle thereto, and means 20 carried by the standard and engageable 25 with the end of the arm to longitudinally adjust the arm with respect to the standard for retaining the said plate in angularly adjusted position.

In testimony whereof I affix my signature 30 in presence of two witnesses.

VESPER I. ARMSTRONG.
